UNITED STATES PATENT OFFICE.

ALBERT COWELL, OF KIDDERMINSTER, ENGLAND.

DESIGN FOR A CARPET-PATTERN.

Specification forming part of Design No. 5,710, dated March 26, 1872.

To all whom it may concern:

Be it known that I, ALBERT COWELL, of Kidderminster, in the county of Worcester, in England, have invented a new and Original Design for Carpets; and I do hereby declare that the following is a full, clear, and exact description thereof, which will enable others skilled in the art to make and use the same, reference being had to the accompanying photographic illustration forming part of the specification.

This invention relates to a new general design for a carpet; and consists in the arrangement of a lozenge-shaped main figure, embraced by a lozenge-shaped border, and embellished by a pendent wreath of flowers that is suspended from a graceful scroll which projects from a ring, all as shown in the photograph.

I claim as my invention—
The design for carpets, as shown.

ALBERT COWELL.
